HEAT CONTROL APPARATUS

Irving C. Jennings, South Norwalk, Conn.

Application August 28, 1935, Serial No. 38,256

5 Claims. (Cl. 236—91)

This invention relates to apparatus for regulating and controlling the temperature within a dwelling house or other building. The heat loss of a building varies not only with the outside temperature but also with the construction of the building, the direction and velocity of the wind, the prevalence of sunshine, snow or rain, whether the outer walls are wet or dry, and whether there is daylight or darkness. Any heat control apparatus which does not take these varying conditions into account may fail to meet the actual requirements by as much as twenty-five or thirty percent.

It is the general object of my invention to provide heat-control apparatus which will maintain a practically constant predetermined temperature within a building and which will avoid either overheating or under heating under widely varying outside conditions.

20 A more specific object of my invention is to provide apparatus which will automatically select and maintain steam pressures which will balance the actual heat loss of a building under varying outside temperature and weather conditions, and 25 which will be thereby effective to maintain a predetermined temperature within said building.

My invention further relates to arrangements and combinations of parts which will be herein-after described and more particularly pointed out 30 in the appended claims.

A preferred form of the invention is shown in the drawings, in which

Fig. 1 is a sectional side elevation of my improved heat-control apparatus, together with a 35 partial section of a building wall;

Fig. 2 is a sectional end elevation, taken along the lines 2—2 in Fig. 1;

Fig. 3 is a detail end elevation, looking in the direction of the arrow 3 in Fig. 1;

40 Fig. 4 is a detail end view, looking in the direction of the arrow 4 in Fig. 1;

Fig. 5 is a detail view, looking in the direction of the arrow 5 in Fig. 1;

45 Fig. 6 is a sectional view, taken along the curved line 6—6 of Fig. 2;

Fig. 7 is a diagrammatic view of a heating system embodying my improvements, and

Fig. 8 is a wiring diagram.

50 Referring to Figs. 1 to 6, I will first describe my improved heat-control apparatus, generally designated A. In Fig. 1 I have shown a casing 10 secured to the inner face of an outside wall W of a dwelling house or other building. The casing 10 is surrounded with a thick layer 11 of heat-

insulating material which may be enclosed by an outer metal cover 12.

The space within the casing 10 is separated by a partition 14 into two chambers 15 and 16. The chamber 15, which may be termed the "reference" 5 chamber, is provided with a heating coil or resistance 17 and a thermostat 18 which may be of any usual construction.

The thermostat and coil cooperate to maintain a constant temperature in the chamber or compartment 15 and the heavy heat-insulating layer 11 makes the temperature condition within the chamber 15 practically independent of the room temperature in which the device is located.

Any desired temperature may be maintained 15 in the chamber 15 but the thermostat is commonly set to maintain a temperature slightly above the desired temperature to be maintained in the building. The partition 14 is of such material and thickness that only a slow transfer 20 of heat between the chambers 15 and 16 can take place.

The outer side of the chamber 16, which may be termed the "control chamber", is preferably closed by a thin metal plate 20 having openings 21 therein. The casing 10 and plate 20 may be secured to the inner face of the outer wall W by screws 22. A suitable gasket 23 may be interposed between the plate 20 and the wall W.

Holes 25 are provided in the outer wall W in 30 alignment with the openings 21 in the plate 20. The chamber 16 is thus insulated from the inside of the building and is directly exposed to weather conditions at the outside of the building.

Discs 27 (Figs. 1 and 5) are provided with different sized openings 28 or no opening which may be selectively brought into alignment with the openings 25 through the wall.

The control chamber 16 contains a circuit-shifting apparatus which is thermostatically controlled. The exact construction of this mechanism may be widely varied but in the drawings I have shown a bi-metal spiral spring 30 (Figs. 1 and 3) having one end secured to a fixed support by a screw 31 and having its other end 45 secured to a rotatable shaft 32 on which is mounted a hub 33 having a slightly resilient arm 34 (Fig. 4) which supports a head 35, preferably formed of non-conducting material.

A spring plunger 36 (Fig. 1) is mounted in a 50 recess in the head 35 and engages a series of contact plates 37, 37^a, 37^b, 37^c and 37^d (Figs. 2 and 6). The contact faces of the plates 37 are preferably concave, as shown in Fig. 6, and the end of the plunger 36 is rounded so that the 55

plunger will always engage one of the plates 37 and will not remain on one of the narrow insulating strips 38 which separate the plates 37. A wire 40 is connected with the plunger 36 and a series of wires 41, 41^a, 41^b, 41^c and 41^d to the plates 37.

A heating system in which my invention may be embodied is illustrated in Fig. 7 as comprising a boiler B, one or more electric motorized valves 10 V, and a plurality of pressure selective controls 42^a, 42^b, 42^c and 42^d marked respectively 1 lb. 5" 10" and 20" and connected by the wires 41^a, 41^b, 41^c and 41^d to my improved control apparatus indicated at A. I also show a high vacuum controller 44 and a low vacuum controller 45 for a vacuum and condensation return pump P. By way of illustration, I have shown my invention as used in a vacuum steam heating system, such a system being indicated in Figs. 7 and 8. The disclosed heating system and its component parts form no part of my present invention, except as certain parts cooperate with my novel heat control apparatus A.

A brief statement of the operation of this heating system is presented in order that the application of my invention to the disclosed system may be more clearly understood.

Line wires L and L' are connected to a step-down transformer T and secondary wires 60 and 30 61 connect the transformer T to the heating coil or resistance 17 in the control apparatus A.

A branch wire 40 connects the wire 60 to the plunger 36 (Fig. 1) on the arm 34, which plunger is shown as having just advanced from the "no-heat" contact point 37 to the contact point 37^a which corresponds to a 20" vacuum in the heating system and to a very low rate of heat dissipation. The contact point 37^a is connected through a wire 41^a to the mercury switch device 42^a, which is one of the devices which control the steam pressure on the supply side of the heating system.

The circuit is continued from the pressure-controlled mercury switch device 42^a through the 45 wires 63, 64 and 65 to a coil 66 which is one of the field coils of the split field motor M which operates the motorized valve V (Fig. 7). This field coil 66 acts to open or partially open the valve V.

50 The circuit is continued through the brush gear and commutator of the motor M and through a wire 67 to the secondary return wire 61 which leads back to the transformer T.

When this circuit is closed and rendered operative by engagement of the plunger 36 with the contact 37^a, the energizing of the field coil 66 causes the motor M to rotate in a direction to partially open the valve V in the main steam line, so that steam at a 20" vacuum will be provided 55 on the supply side of the heating system.

A solenoid 70 is inserted in the wire 41^a previously described, and passage of current through the wire 41^a and solenoid 70 causes engagement of contacts 71 and 72, thus closing a connection 65 between wires 73 and 74.

The wire 73 is connected to one side of a double pole switch 75 in the high vacuum controller 44. The second side of the double pole switch 75 is connected to a wire 76 which in turn is connected 70 to a line wire in the magnetic starter S of the vacuum and condensation-return pump P.

The starter control circuit is then complete, as the wire 76 is continuously connected to a second line wire in the starter S. The motor M and 75 pump P will thus be started, and will continue to

operate until the desired 20" vacuum is attained on the supply side of the heating system.

The pressure-controlled device associated with the mercury switch 42^a (Fig. 7) then moves the switch to mid-position and thus stops the motor M.

The pump P will continue to operate until the high vacuum controller 44 opens the double pole switch 45 associated therewith, which will ordinarily be at a little higher vacuum, say twenty-two inches. This gives a differential pressure of two inches of mercury or approximately one pound which is operative on the low pressure steam and causes the low pressure steam to have a positive circulation and to deliver mild heat.

If the pressure in the supply side of the system now rises above twenty inches of vacuum, the mercury switch in the pressure-controlled device 42^a will then be reversed, connecting the wire 41^a through the wires 80 and 81, field coil 82 and 20 valve motor M to the wire 67 and secondary return wire 61. The valve motor M will thus be operated reversely to partially close the valve V on the supply side of the system.

If the plunger 36 (Fig. 1) in the control device 25 A advances to engage the 10" vacuum contact 37^b, the circuit will be similarly closed through the wire 41^b and solenoid 84 to the pressure-controlled switch device 42^b, and back through the wires 64 and 65, field coil 66, motor M and wire 67 to the secondary return wire 61, thus causing the motor M to rotate in a direction to further open the valve V and effect a 10" vacuum.

Current through the solenoid 84 causes engagement of contacts 87 and 88 which are connected 35 by branch wires 89 and 90 to the wires 73 and 74 in parallel with the contacts 71 and 72 in the 20" circuit. Engagement of the contacts 87 and 88 thus acts to complete the circuit between the high vacuum controller 44 and through the magnetic starter S for the pump P, which will then be operated as previously described, except that the motor M will be stopped by the mercury switch of the pressure-controlled device 42^b when a 10" vacuum is attained on the supply side of 45 the system, but the pump P will continue to operate until shut off by the high vacuum controller 44 at the same high vacuum of 22" previously defined.

If the plunger 36 advances to the 5" vacuum 50 contact 37^c, a circuit is completed through the wire 41^c to the pressure-controlled switch device 42^c, and back through the wires 64 and 65, field coil 66, motor M and wire 67 to the secondary return wire 61, the motor thereupon being operated 55 to further open the valve V and effect a 5" vacuum. The valve motor M is stopped by the pressure-controlled device 42^c on attainment of the desired 5" vacuum.

Similarly, engagement of the plunger 36 with the 1 lb. contact 37^d completes the circuit through the wire 41^d and pressure-controlled switch device 42^d to operate the motor M and to further open the valve V to effect 1 lb. pressure in the supply line, and on reversal of the mercury switch of 65 the device 42^d for excess pressure on the supply side the field coil 82 is energized to reverse the motor M.

When the plunger 36 is in engagement with contacts 37^c and 37^d, the magnetic starter S is 70 also under the direct control of the low vacuum controller 45 and of the float switch control 92. A low vacuum (say ten inches) gives a sufficiently active circulation when the pressure on the supply side is not very much above or below at-

mospheric, which condition obtains when the plunger 36 is on one of the contacts 37^c or 37^d.

When the plunger 36 is in engagement with the contact 37 marked "off", the circuit is complete through the wire 41 to the wire 81 and thence through the field coil 82, which then causes the motor M to operate to close the valve V. For a more complete description of the construction and operation of the heating system and thermostatic-controlled, valve-adjusting mechanism, reference is made to my copending application Serial No. 754,674, filed November 24, 1934.

The operation of my improved heat control apparatus is as follows:

The control chamber 16 of the heat-control apparatus A is held against the outer wall W and also communicated with the atmosphere through the passage 25. The freedom of this communication may be varied by changing the setting of the disc 27. The temperature in the control chamber 16 thus responds directly to all variations in external weather or temperature conditions. The temperature of the chamber is also affected by the exchange of heat with the reference chamber 15.

The invention aims to control the heat supplied to the building in proportion to the heat lost through the outside walls, so that the building will be maintained at constant temperature under varying conditions. When the wind blows harder or the walls become wet, more heat is required, even although the outside temperature has not changed.

The thermostat 30 responds to the temperature in the chamber 16 and varies the setting of the plunger 36 on the contact plate 37 in accordance with the demand for heat, as indicated by the temperature in the control chamber 16.

The heat control or heat regulation can thus be said to respond to the differential between the constant temperature in the reference chamber 15 and the actual temperature in the control chamber 16, corresponding to the external weather and temperature conditions. As both chambers 15 and 16 are heavily heat-insulated, the apparatus is independent of local variations of temperature within the building.

In mild weather when the temperature in the control chamber 16 is only slightly less than that in the reference chamber 15, the plunger 36 will be in the "off" position the greater part of the time. As the severity of the weather or its unfavorable characteristics increase, increase in steam pressure will be supplied.

While I have shown my invention in use to control heating apparatus of the vacuum type, the invention is not limited to any one type of heating apparatus and it may be used in pressure systems of steam heating or in hot air or hot water systems as well as in vacuum heating systems.

Having thus described my invention and the advantages thereof, I do not wish to be limited to the details herein disclosed, otherwise than as set forth in the claims, but what I claim is:

1. Heat control apparatus effective to maintain a predetermined temperature within a building under varying outside weather conditions, which apparatus comprises a heat-insulated casing contained within the building and abutting an outside wall thereof, said casing having one interior chamber remote from said outside wall which is automatically maintained at a substantially constant temperature approximately equal to said predetermined temperature and having a second

interior chamber adjacent said outside wall and in which the temperature is responsive to outside temperature and weather conditions, said first and second interior chambers being in heat-interchanging communication, a thermostat located at an intermediate point in said second chamber, and means controlled by said thermostat and effective to maintain a substantially constant predetermined temperature in said building.

2. Heat control apparatus effective to maintain a predetermined temperature within a building under varying outside weather conditions, which apparatus comprises a heat-insulated casing contained within the building and abutting an outside wall thereof, said casing having an enclosed air chamber maintained at substantially constant temperature and having a second and adjacent enclosed air chamber in which the temperature is responsive to outside weather and temperature conditions, means permitting restricted interchange of heat between said chambers, and heat control devices operated in accordance with changes in temperature at a predetermined point in said second chamber.

3. Heat control apparatus effective to maintain a predetermined temperature within a building under varying outside weather conditions, which apparatus comprises a heat-insulated casing contained within the building and abutting an outside wall thereof, said casing having an enclosed air chamber maintained at substantially constant temperature and having a second and adjacent enclosed air chamber in which the temperature is responsive to outside weather and temperature conditions, said air chambers being separated by a partition allowing a slow heat exchange between said air chambers, and heat control devices operated in accordance with changes in temperature at a predetermined point in said second chamber.

4. Heat control apparatus effective to maintain a predetermined temperature within a building under varying outside weather conditions which comprises a reference chamber within said building and automatically maintained at a substantially constant temperature approximately equal to said predetermined temperature, a control chamber exposed in part to outside weather conditions and adapted to be secured to the inside of an outer wall having openings therethrough, means permitting slow transfer of heat from said reference chamber to said control chamber, a thermostat located at a fixed point in said control chamber, and heating apparatus for said building controlled by said thermostat.

5. Heat control apparatus effective to maintain a predetermined temperature within a building under varying outside weather conditions which comprises a heat-insulated casing contained within the building and abutting an outside wall thereof, said casing containing a reference chamber automatically maintained at a substantially constant temperature approximately equal to said predetermined temperature, an adjacent control chamber exposed in part to outside weather conditions and adapted to be secured to the inside of an outer wall having openings therethrough, means to variably restrict said openings, means permitting slow transfer of heat from said reference chamber to said control chamber, a thermostat located at a fixed point in said control chamber, and heating apparatus for said building controlled by said thermostat.

IRVING C. JENNINGS.
